Patented Aug. 19, 1924.

UNITED STATES PATENT OFFICE.

FERNAND HOLWECK, OF PARIS, FRANCE, ASSIGNOR TO MULLARD RADIO VALVE COMPANY LIMITED, OF LONDON, ENGLAND, A BRITISH COMPANY.

RADIOLOGICAL APPARATUS.

Application filed November 18, 1922. Serial No. 601,791.

To all whom it may concern:

Be it known that I, FERNAND HOLWECK, a citizen of the French Republic, residing in Paris, France, have invented certain new and useful Improvements in Radiological Apparatus (for which I have filed an application in France on November 15, 1921, application No. P. V. 151,895), of which the following is a specification.

10 All the existing types of apparatus for producing X-rays and like radiations consist of two principal parts connected by means of conductors passing generally through the surrounding air; for example, 15 a high tension transformer and an X-ray tube when it is desired to increase (as is important in X-ray work) the power of the installation and particularly the difference of potential at the terminals of the glass 20 tube, grave difficulties are encountered. It is necessary to separate by a considerable distance the high tension leads in order to prevent spark discharge, but brush discharge loss and danger are not avoided; 25 X-ray tubes, which are costly, are always made of glass, and must be very long and must be immersed in oil, but even this frequently does not prevent them being pierced by sparks; once damaged, they can only be 30 repaired by the maker. The localizing of the active beam or pencil, without the production of secondary rays, becomes very difficult on account of the large volume which the localizer takes because it ought 35 not to be removed from the tube. Finally, it is impossible to dissipate the large heat losses from the interior of a glass tube.

The apparatus which is the subject of this invention and of which one method of 40 construction is shown in the accompanying drawing by way of example, is a remedy for the above defects by means of the following arrangements:

45 The high voltage transformer 1, with closed or open magnetic circuit, is placed in a metallic chamber, or covered by means of a conducting envelope 2, filled with a dielectric other than air, as for example oil. This transformer has one of its terminals 50 3 connected to the chamber and to earth 4. The other end 5 of the high tension winding enters a metallic tube 7 fastened to the chamber and filled with a dielectric other than air. The X-ray tube 8 is entirely metallic and is an extension of the tube 7, be-

ing at the same time united electrically with it, that is to say, with the chamber, the earth and one of the terminals of the transformer. The anticathode 9 can be cooled by means of the circulation of water or any 60 other fluid, which can also be used to cool the body 8 of the tube. The vacuum is produced in the ray-generator through the tube 10, by means of a pump which for example may operate during the whole time 65 of use of the apparatus. The insulation of the electrode 5, 6, on which the electrical tension is very high, between the transformer chamber filled with oil and the ray-producing-tube, evacuated of air, can be of 70 glass or other insulating material.

The gaskets 12, and 13, between this insulating piece 11, the electrode 5 on one hand and the tube 14 on the other hand can be of the type of those shown in my French 75 Patent No. 137,949 applied for 11th February 1921.

The tube 8 in which the rays are produced is constructed with walls sufficiently thick 80 in order to completely absorb the rays except in one part where a thin window may be arranged. This window 15 may be for example of aluminum. A gasket 16 can be arranged in order to permit of the orientation of the beam of rays by rotation of the cylinder 8 around its axis and a gasket 17 85 can be provided in order to permit of easily dismantling the tube and for example, replacement of the electrodes 6 and 9.

What I claim as my invention and desire 90 to secure by Letters Patent is:—

1. An apparatus for radiology, the combination of a high tension transformer, an electrically conducting container wherein the transformer is immersed in a dielectric 95 other than air, an electric connection between one secondary terminal of the transformer and the container, and a vacuum tube mounted on the outside of the container comprising a metallic envelope constructed 100 of separable parts electrically connected to the container and a cathode electrically connected to the other secondary terminal of said transformer through a part of the wall 105 of the tube which is in direct contact with the dielectric in the container.

2. In apparatus for radiology, the combination of a high tension transformer, an electrically conducting container wherein the transformer is immersed in a dielectric 110

other than air, an electric connection between one high tension terminal of the transformer and the container, and a vacuum tube mounted on the outside of the 5 container comprising a metallic envelope connected to the container and a cathode electrically connected to the other high tension terminal of said transformer through a part of the wall of the tube which is in di-

rect contact with the dielectric in the container, one of which parts of said envelope 10 has a window for the passage of a beam of rays, which window part is so mounted as to permit of rotating the window about the longitudinal axis of the tube while the 15 transformer container remains stationary.

In testimony whereof I affix my signature.
FERNAND HOLWECK.
